DESIGN FOR A COLLAR OR SIMILAR ARTICLE

Walter F. Breuss, Leonia, N. J.

Application December 28, 1938, Serial No. 82,022

Term of patent 3½ years

To all whom it may concern:

Be it known that I, Walter F. Breuss, a citizen of the United States, residing in Leonia, county of Bergen and State of New Jersey, have invented a new, original, and ornamental Design for a Collar or Similar Article, of which the following is a specification, reference being had to the accompanying drawing, forming part thereof.

The figure is a top plan view of a collar showing my new design.

I claim:

The ornamental design for a collar or similar article, as shown.

WALTER F. BREUSS.
